G. BROWNING

RAZOR

Original Filed Aug. 12, 1921

Patented Aug. 18, 1925.

1,550,424

UNITED STATES PATENT OFFICE.

GEORGE BROWNING, OF CHICAGO, ILLINOIS, ASSIGNOR TO LEE RAZOR MANUFACTURING COMPANY, OF CHICAGO, ILLINOIS, A CORPORATION OF DELAWARE.

RAZOR.

Application filed August 12, 1921, Serial No. 491,683. Renewed June 29, 1925.

To all whom it may concern:

Be it known that I, GEORGE BROWNING, a subject of the King of Great Britain, residing in the city of Chicago, in the county 5 of Cook and the State of Illinois, have invented certain new and useful Improvements in Razors, of which the following is a specification, reference being had to the accompanying drawings, forming a part thereof.

10 This invention relates to a safety razor of the type in which the blade is arranged to oscillate in the direction of its cutting edge, and one object of the invention is to provide mechanism for obtaining a more 15 rapid oscillation of the blade than has been possible with previous devices of this type. Other objects of the invention relate to the convenience of manufacture or convenience of use, and are concerned with various de-

20 tails of the structure. The invention, therefore, consists in the features and elements of construction and their combination hereinafter described and shown in the drawings, as indicated by the claims.

25 In the drawings:

Figure 1 is a top plan view of the blade-carrying head of the razor with a blade mounted thereon, but with the retaining guard swung clear of the blade to disclose 30 the structure.

Figure 2 is a side elevation of the parts shown in Figure 1, with a portion of the handle attached, and with certain parts shown in section.

35 Figure 3 is a transverse section taken substantially as indicated at line 3—3 on Figure 2, but with certain parts broken away or shown in section below the principal plane of the section.

40 Figure 4 is a detail section taken as indicated at line 4—4 on Figure 2.

Figure 5 is a detail section taken as indicated at line 5—5 on Figure 3.

As shown in the drawings, the blade 1, 45 is removably carried by a frame or head which comprises a top plate, 2, and a bottom plate, 3, secured together in spaced relation by a pair of posts, 4, carrying spacer sleeves, 5. At their lower ends said posts 50 are centrally bored and riveted over at 6, and to improve the appearance, headed finish studs, 6^a, may be added as shown in Figure 2. At their upper ends the heads, 7, of the posts, 4, serve as guides for controlling the oscillation of the blade, 1, by en-

gagement in its slots, 1^a, as seen in Figure 1. At its forward edge, the bottom plate, 3, is bent obliquely upward to provide a support, 8, for the bent guard member, 9, of U-shaped cross section, whose slotted edge stands adjacent the cutting edge of the blade, 1. The parts, 8, are bent forwardly in lugs, 10, which provide journal bearings for a crank shaft, 11, carrying the traction wheels, 12, from which motion is transmitted for oscillating the blade, 1. A boss, 13, formed in the bottom plate, 3, or permanently secured thereon, supports a threaded stud, 14, to which the handle, 15, is removably applied.

At its forward edge, the top plate, 2, is formed with several, preferably three, lugs or projections, 2^a, which are bent slightly up from the plane of the plate to provide bearing surfaces of limited extent for the blade, 1, just back of its cutting edge. Near the opposite edge the blade will bear on the top plate, 2; but said opposite edge of the blade being sharpened and beveled, its cutting edge will stand clear of the bottom plate, and will not be dulled by contact therewith. A swinging guard member, 16, overhangs the blade when the latter is in use, and a boss, 17, formed on the under surface of said guard, presses upon the upper side of the blade to hold it firmly against the top plate, 2, as it oscillates. The guard, 16, is bent downwardly at the rear side of the head and terminates in forwardly trending ears, 18, pivoted upon a headed pin, 19, to provide a hinge upon which the guard member is swung clear of the blade, 1, to permit removal of the latter. The hinge pivot, 19, is carried by lugs, 20, bent forward from the depending extension, 21, of the top plate, 2, and for securing the guard, 16, in position to retain the blade, 1, a swinging latch member, 23, is pivoted at 24, to the rear wall of the guard with its upper end, 25, off-set to engage under the part, 21, as seen in Figure 2. Said part, 21, has an oblique clearance notch, 26, through which the opposite end, 25, of the latch, 23, may emerge when the latch is swung to the position shown in full lines in Figure 4.

For operating the latch, a handle or finger piece, 27, is formed at its lower end below the pivot, 24, so that the guard plate, 16, may be positively locked or unlocked at will, and swung to a position shown by dot- 105 110

and-dash lines in Figure 2, when it is desired to remove or replace a blade.

The traction wheels, 12, running on the surface of the skin as the razor is drawn over the face, provide the motion for oscillating the blade, 1. To improve their tractive quality, therefore, it is preferable to make the surfaces toothed or serrated, and for the best efficiency, the teeth, 12^a, should resemble those of a ratchet wheel, trailing or raked back from the direction of operative rotation of the wheels, so that the faces, 12^b, which actively engage the surface of the skin, shall initially engage said surface at a sharper angle, thus minimizing the chance of slip. The single throw crank shaft, 11, driven by the wheels, 12, transmits motion through a pitman, 28, to a crank pin or pivot, 29, connecting the rocker arm, 30, and the link, 31. Said rocker arm, 30, is fixedly fulcrumed on a post, 32, carried by the bottom plate, 3, and the link, 31, is pivotally connected at 33, to the oscillator arm, 34, fulcrumed on a post, 35, also supported on the bottom plate, 3.

As shown in Figure 5, the pivots, 29 and 33, may be made integral with the link, 31, by forming the latter of round wire stock and merely bending down the ends. The rocker arm, 30, is made of sheet metal and comprises a duplicate lower arm, 30^a, joined to the upper portion, 30, by a connecting web, 30^b, which spaces the upper and lower arms apart so that together they provide a fairly long bearing for the pivot, 29; and also by this arrangement, ample space is provided for the end of the pitman, 28, on the pivot or crank pin, 29. The oscillator, 34, is similarly formed with a spaced duplicate arm, 34^a, and to insure easy movement of the rocking members the fulcrum posts, 32 and 35, are made with base flanges, 32^a and 35^a, which hold the rockers away from the bottom plate, 3, as shown in Figure 5.

Preferably the pitman, 28, has a broad bearing, 36, on the crank shaft, 11; but the lateral play of the pivot or crank pin, 29, is permitted by a transverse slot, 37, on the pitman. In a half turn of the crank shaft, 11, the toggle composed of the rocker arm, 30, and link, 31, is shifted from the angular position shown in Figure 3 to a straightened position and to the oppositely angular position shown in dot-and-dash outline. This much movement causes the free end, 38, of the oscillator, 34, to swing through the arcuate slot, 39, in the top plate, 2, and back again, while a further half turn of the crank, 11, will produce a second complete oscillation in said slot, 39. The end portion, 38, of the oscillator, 34, is bent to extend through the slot, 39, to engage a transverse slot, 40, in the blade, 1, for driving it; thus each rotation of the crank shaft,

11, causes two complete oscillations of the blade, 1, in the direction of its cutting edge, which combine with the advancing movement of the blade as the razor is drawn over the face, so as to produce a series of short draw cuts, permitting the blade to work to the best advantage.

For convenience of assembling, each of the wheels, 12, has a diametrically extending groove or slot, 41, formed on its inner face to engage and interlock with the crank arm, 11^a, of the crank shaft, 11, as shown in Figure 3. The wheels, 12, are simply slipped on to the ends of the crank shaft, 11, and as the lugs, 10, of the frame are sprung or bent apart, the extreme end portions of the shaft are snapped into the bearing apertures in said lugs; the wheels are thus retained in engagement with the crank arms, 11^a, by the bearing lugs, 10, and no further securing of the parts is required. Preferably the pitman, 28, is made of flat stock with its broad bearing, 36, formed by merely folding one end around the wrist portion of the crank shaft, 11.

As indicated in Figure 1, when a double-edged blade is used, it is preferably formed with two slots, 40, symmetrically located with respect to both its longitudinal and transverse axes, so that if the blade be shifted end for end in changing from one cutting edge to the other, there will still be a slot in position to register with the oscillator arm, 38. However, for distinguishing one cutting edge from the other, so that the user, if he wishes, may use one edge continuously until it becomes too dull, a perforation, 42, is formed in the blade nearer one edge than the other.

I claim:—

1. In a razor comprising a frame and a blade mounted to reciprocate thereon, a link and means operatively connecting it to the blade comprising a rocker arm fulcrumed on the frame with its free end upturned to engage a hole in the blade for driving it, said link being pivotally connected at one end to the rocker arm and at the other end to a crank pin which is guided to traverse a limited arc transversely of the direction of blade reciprocation together with rotary traction means journaled on the frame and a crank and pitman connection between said traction means and the crank pin.

2. In a razor comprising a frame and a blade mounted to reciprocate thereon, a rocker member fulcrumed on the frame for limited rotation between oppositely oblique positions with respect to the direction of blade movement and having a crank pin operatively connected to the blade, said rocker member being formed of sheet metal and comprising upper and lower portions of similar outline with registering perforations at the fulcrum axis and for the crank pin,

- said portions being connected together in spaced relation by a web portion; rotary traction means journaled on the frame provided with a crank and a pitman connecting
- 5 said crank with the crank pin of the rocker member between the upper and lower portions of the latter.
3. In a razor comprising a frame and a blade mounted to oscillate thereon, rotary traction means journaled on the frame provided with a crank and pitman connected thereto, a rocker arm fulcrumed at one side of the pitman path with its end overlapping the pitman, a second rocker arm fulcrumed
- 10 at the other side of the pitman path extending transversely of the direction of blade movement and having its end formed for driving engagement with the blade, and a link of round stock with its end portions bent at right angles to its middle portion, one end of said link forming a pivotal connection with the first rocker and the pitman, and the other end of the link being pivotally engaged with the second rocker for trans-
- 15 mitting motion thereto from the pitman.
4. In the combination defined in claim 3, fulcrum posts for said rockers upstanding from the surface of the frame and provided with spacing flanges adjacent said surface
- 20 for holding the rockers away from it.
5. In a razor comprising a frame and a blade mounted to oscillate thereon, rotary traction members journaled on the frame and provided with a crank and pitman connection for actuating the blade, said traction members comprising a pair of toothed wheels, each having a diametrically grooved hub, said wheels being carried loosely on opposite ends of a bent crank shaft adjacent
- 25 supporting lugs in which the end portions of the shaft are journaled, the crank portion of said shaft serving to space the wheels apart between said supporting lugs and the crank arms of the shaft engaging the diametral grooves of the wheel hubs for driving engagement therewith.
6. In a razor comprising a frame and a blade mounted to oscillate thereon, rotary traction means journaled on said frame and
- 30 provided with driving connections for actuating the blade, said means including a
- wheel or roller having a toothed or serrated surface, the teeth being shaped to resemble those of a ratchet wheel with the body of each tooth inclined away from radial direction and trailing with respect to the direction of rotation of the wheel during a working stroke of the razor.
7. In a razor comprising a frame and a blade mounted to oscillate thereon, said frame having a plate formed to support said blade adjacent its front and rear edges, said plate having a down-turned area at its rear edge with lugs supporting the hinge pivot of a bent cover plate or guard adapted to
- 35 overhang the blade, and a latch arm pivoted to a part of said cover adjacent the downwardly bent part of the frame plate, said frame plate having a notch adapted to accommodate said latch arm when the cover
- 40 is folded toward the frame and the arm having an offset end portion for engaging the inner side of the frame to retain the cover adjacent the blade but releasable through said notch when the latch lever is
- 45 swung about its pivot.
8. In a razor comprising a frame which includes substantially parallel upper and lower plates with posts connecting them and spacers on said posts, a blade mounted to
- 50 oscillate on the upper plate of said frame, with means for retaining it thereon, rotary traction means journaled on the frame provided with a crank and pitman, a pair of rockers each fulcrumed on a post supported
- 55 in the lower plate of the frame and extending adjacent the upper plate, a link formed of round stock with down-turned ends pivotally engaging said rockers respectively, the middle portion of said link being accommodated between the rockers and the upper plate of the frame and being thus retained by the proximity of said plate, the pitman being pivotally connected to one of
- 60 the rockers and the other rocker having a part extending through the upper plate for
- 65 engaging the blade to actuate it.
- In testimony whereof, I have hereunto set my hand at Chicago, Illinois, this 9th day of August, 1921.

GEORGE BROWNING.
